208,425

COMBINATION CIGARETTE LIGHTER AND PIPE STUFFING, CLEANING AND CLEARING TOOLS

Robert Hocq, Boulogne-Billancourt, France, assignor to Societe Franco Hispano Americaine Francispam, Paris, France

Filed Aug. 1, 1966, Ser. No. 3,306

Term of patent 14 years

(Cl. D48—27)

FIG. 2.

FIG. 1

FIG. 4

FIG. 1 is a perspective view from the bottom showing one side of the lighter and of the set, with the set in the closed state, and the other side is similar.

FIG. 2 is a bottom view with the set in the closed state.

FIG. 3 is a perspective view from the top showing one side, with the set in the open state to show the shape of the three tools.

FIG. 4 is a perspective view from the bottom showing the other side, with the set in the open state.

I claim:

The ornamental design for a combination cigarette lighter and pipe stuffing, cleaning and clearing tools, as shown and described.
